US00D844004S

(12) **United States Design Patent** (10) **Patent No.:** **US D844,004 S**
Ishida et al. (45) **Date of Patent:** **** Mar. 26, 2019**

(54) **SCANNER**

(71) Applicant: **PFU LIMITED**, Kahoku-shi, Ishikawa (JP)

(72) Inventors: **Shoya Ishida**, Kahoku (JP); **Satoshi Kuroda**, Kahoku (JP); **Keisuke Kokuma**, Kahoku (JP)

(73) Assignee: **PFU LIMITED** (JP)

(**) Term: **15 Years**

(21) Appl. No.: **29/632,996**

(22) Filed: **Jan. 11, 2018**

(30) **Foreign Application Priority Data**

Jul. 31, 2017 (JP) 2017-016478

(51) **LOC (11) Cl.** **14-02**

(57) **CLAIM**

The ornamental design for a scanner, as shown and described.

DESCRIPTION

FIG. 1 is a perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is another perspective view thereof in open position. The broken lines in the drawings are for the purpose of illustrating unclaimed portions of the scanner and form no part of the claimed design.

1 Claim, 5 Drawing Sheets
